FIG. 13.

Franz Hetzelberger, ^{Inventor}

By *Conway J. D.*

Attorney

UNITED STATES PATENT OFFICE.

FRANZ HETZELBERGER, OF ULM-ON-THE-DONAU, GERMANY, ASSIGNOR TO C. D. MAGIRUS, AKTIENGESELLSCHAFT, OF DONAU, GERMANY, A CORPORATION OF GERMANY.

SAFETY DEVICE FOR PORTABLE POWER-OPERATED FIRE ESCAPES.

Application filed August 29, 1925, Serial No. 53,443, and in Germany May 12, 1925.

In power operated travelling or portable fire escapes, the gears operating the escapes or ladders, are automatically controlled in such a manner that they stop the movement 5 of the escape before the tilting or turning-over limit is reached, to prevent upsetting the vehicle. In the known constructions the conditions on striking an obstacle during the extending, raising or inclining of the 10 escape, are insufficiently taken into account.

The invention relates to a safety device for portable fire escapes which stops the operation of the gears also in these cases, to prevent turning over of, or damage to, the vehicle and the escape. To this end, the frame or bed supporting the escape or ladder is resiliently mounted on its turntable or ring so that when the escape is overloaded, for instance when it strikes an obstacle when being extended, raised, or inclined, it deviates from its normal position, and means are provided which due to this deviation operate to stop the operation of the gears. 20

Several constructions according to the invention are illustrated by way of example in the accompanying drawing in which

Figure 1 shows an escape supporting frame or bed in side elevation,

Figure 2 shows the same in rear elevation, 30 partly in section.

Figure 3 is a detail view in section.

Figures 4, 5 and 5^a show modified constructions.

Figure 6 is a detail view and Figure 7 a 35 modification of the same.

Figures 8 to 12 are diagrams.

Fig. 13 is a side elevation showing the ladder elevating and extending mechanism.

The life saving apparatus or fire escape 40 herein shown is generally similar to that described in the patent to Mayer No. 1,528,448, issued March 3, 1925, and only such portions of the apparatus as are intimately related with the novel features of this invention 45 will be described in detail herein, and for further information as to details of construction of the escape reference may be had to the prior patent.

In general the apparatus comprises a 50 frame 1 which carries and supports the escape or ladder. The reference character A denotes generally a fluid pressure or hydraulic mechanism by means of which the ladder is operated. Projecting from the

actuating mechanism are driving shafts B 55 and C, the latter acting through mechanism hereinafter described to elevate the ladder while the former shaft serves to produce an extending or telescoping movement. Power is transmitted from the driving shaft C to 60 an erection spindle D by suitable gear mechanism generally indicated at E. The spindle D is externally threaded and has mounted thereon an internally threaded nut F fixed to the lower end of a tube G, the latter being pivoted at its upper end as at H to a laddered carrying member I mounted upon the horizontal axis J. From this construction, it will be apparent that the ladder carrying member I may be moved about its 65 horizontal supporting pivot in either direction by the rotation of shaft C. The driving shaft B is connected by chains or belts K and L to an elevating drum M, the movement of which is utilized to effect the extension or telescoping of the ladder. Neither the form of the extensible ladder or escape 70 employed nor the connection between such element and the elevating drum M constitutes an essential part of the present invention, and, therefore, will be described only generally, it being understood that various extensible ladders may be employed to advantage and that the present form is shown for purposes of illustration only. 75

The ladder illustrated in Fig. 13 comprises plurality of sections N, O, P, Q adapted to move telescopically with respect to each other. A wire rope or cable R secured to the extending drum is wound on and off the 80 drum when the latter is rotated in a clockwise or counterclockwise direction respectively. The free end of the cable R passes over a pulley S mounted near the top of the ladder section N, and is secured at the bottom of the second ladder section O. When the cable is wound up on the drum, the second ladder section which is slidably mounted on the first ladder section will be extended. The end of a second cable T is secured to the top of the ladder section N and passes over a pulley U mounted near the top of a second ladder section O and is secured to the bottom of the third section P. The extension of the second ladder section will, by means of this cable, extend the third section in a manner clearly understood. The end of a third cable V is secured to the up- 85 90 95 100 105

per end of the ladder section O, passes over a pulley W near the top of the third ladder section, and is secured to the bottom of the fourth ladder section Q. An upward movement of the ladder section P will also move the section Q in a similar manner. Thus, the winding of the cable R on the drum M will extend all of the ladder sections. When the cable R is unwound from the drum by rotation of the latter in a clockwise direction, the sections of the ladder will move downwardly to finally assume the position indicated in Fig. 13. Rotation of the driving shafts B and C is effected by fluid operated gears within the mechanism A, the said gears being in turn connected to a convenient source of power. Control cocks 21 and 22 are provided through which the fluid or liquid intended to operate the mechanism is conducted as desired to the various gears within the mechanism A where the power is to be applied.

The escape supporting frame or bed 1 is rotatably mounted on trunnions 6 in bearings 7 on an upper turntable 2 which is mounted in an easily rotatable manner by means of balls 4 on the lower ring 3. In order to prevent the upper ring or turntable 2 from being lifted off the lower ring 3, it is provided with abutments 5 in the form of rollers adapted to engage a circular flange formed upon the upper edge of the lower ring 3. The escape supporting frame 1 is spaced a distance 8 from the turntable 2 and is supported by pressure parts 9 and 10 slidably mounted in the turntable 2. The lower ends of members 9 and 10 are formed in the shape of knife edges, similar to balance beams, adapted to rest on double levers 11, 12 which are pivotally mounted on the turntable 2 by means of brackets or bearings 13, 14. The free ends 15 of the two double levers 11, 12 are provided with slots 15' in which is mounted a pin 17. This pin is mounted on a rod 18 which is pivoted to a depending rod 16' enclosed within a casing 16''. A spring 16 surrounding the rod 16' is provided within the casing to resist upward movement of the rod, the spring being arranged to abut against a washer on the lower end of the rod and its upper end engages a stationary abutment such as the cover of the casing. The operation and construction of the gear operating mechanism is described in detail in the Mayer Patent 1,528,448 and since such mechanism does not constitute an essential part of the present invention, a detailed description is not believed necessary in this application. The spring 16 is adjusted in such a manner that it balances the escape supporting frame 1 with the whole escape superstructure and the admissible load on the escape. The rod 18 is adapted to act on levers 19, 20 of control members 21, 22 which are connected by pipes

56, 57, Figure 3, to hydraulic couplings 54, 55 of a gear by which are produced in the well-known manner the movements of the escape (extending and raising).

In normal conditions and within the admissible load limits, the levers 19, 20 of the control members 21, 22 are released by the rod 18, and the control members of the gears may be adjusted by hand by means of the levers 23, 24, rods 25, 26 and hand levers 27, 28.

In the event however of the escape being overloaded or of it striking an obstacle, so that there is risk of the escape being upset or broken, the escape supporting frame 1 will be slightly depressed at the side where the excess of pressure has occurred, by overcoming the pressure of the spring 16 by means of the pressure parts 9 and 10 and one of the levers 11 or 12, whilst the other lever 12 or 11 will not be moved owing to the slot connection. The rod 18 will thereby become raised (see dotted lines in Figure 1) and will turn the levers 19, 20 upwards and lock the control members 21 and 22, owing to which the pressure medium for operating the couplings 54 and 55 of the gear, Figure 3, will be cut off, so that it will be impossible to operate the control members 21 and 22 by hand, and the gears for operating the escape will stop.

In the construction shown in Figure 4, the escape supporting frame 1 is rigidly connected to the turntable 2 but the abutments formed by rollers 5, are secured to a separate holding ring 29 which, by means of springs 31 and pins 32 resting against the turntable 2, is held in a springy manner against the turntable 2 so that it is at a distance 30 from the same. On the holding ring 29 are rotatably mounted in bearings 33, 34 about pins 37, 38, levers 35, 36 which are further suspended to pins 39, 40 in bearings 41, 42 of the turntable 2. The free ends of the two levers 35, 36 are connected to the rod 18 acting on the levers 19, 20 of the control members 21, 22, by means of a slot-like guide 43, similar to that in the construction shown in Figure 1.

In the event of the escape being overloaded or striking an obstacle, the turntable will be lifted off the lower ring 3, and the lever 35 or 37 will turn upwards about 37 or 38, owing to which the rod 18 will be moved upwards and will stop the operation of the gears by means of the control members 19, 20, 21 and 22.

In the construction shown in Figures 5 and 5^a, the escape supporting frame is also rigidly connected to the turntable 2. The abutments 5 comprising rollers secured to the turntable 2, have a given clearance or play 43 (see Figure 5^a) to the extent of which the turntable 2 can be lifted from the lower ring 3. On the turntable 2, in

bearings 44 and 45 are rotatably mounted on pins 46 and 47, feeler levers 48 and 49 which by means of rollers 50 and 51 engage a surface of the ring 3. The free ends of the levers 48 and 49 are pivotally connected to each other by means of an oscillating lever 52, to the centre of which is pivoted the rod 18 which is surrounded by a spring 53 on the turntable 2. The remaining construction is the same as in Figure 1.

In the case of overload or shock, the turntable 2 will be lifted from the lower ring 3 to the extent 43, owing to which one of the feeler levers 48 or 49 will be turned about the pin 46 or 47 with the short arm downward, and the long arm, and therefore, rod 18 upward.

Figure 6 shows on an enlarged scale the arrangement of the two control members operated by the rod 18, for extending and raising the escape by means of oil pressure operated gear, whilst in Figure 7 the rod 18 acts on a single main supply member 58. The pressure medium, for instance oil, is admitted at *a* and passes through the cock 59 which is connected by a lever 60 to the rod 18, into the pipe *c* or *d*, owing to which the couplings 54 and 55 of the gear of Figure 3 are switched in or out in the manner clearly illustrated in the Mayer patent previously referred to.

Figure 8 shows diagrammatically the maximum extension admissible for a given inclination of the escape. The gear stopping device must in this instance act in such a manner as to avoid any turning over of tilting of the escape by further extension or inclination. If the escape strikes an obstacle when being extended, raised and laid down within this prescribed limit, or in the case of strong wind shocks or other accidents, the tilting moment will be increased. The devices shown in Figure 1-7 then effect the stopping of the gears operating the escape, in order to avoid an accident or breakage of the escape.

Figure 9 shows diagrammatically the load proportion and the method of operation of the gear stopping mechanism in the case of the escape 61 being extended and inclined too much, as well as in the case of wind shocks and like overloads.

Figure 10 shows the load and the method of working in the case of striking an obstacle 62 when being extended.

Figure 11 shows the conditions due to striking a projection 63 in raising, and Figure 12 due to striking an obstacle in lowering.

Having now particularly described and ascertained the nature of my said invention and in what manner the same is to be performed, I declare that what I claim is:—

1. A salvaging apparatus having an extensible ladder, a frame for supporting said

ladder, a support for said frame, operating mechanism for extending and telescoping said ladder, operating mechanism for elevating and lowering said ladder, and means operated by movement of the supporting frame out of its normal position for stopping said operating mechanisms. 70

2. A salvaging apparatus having an extensible ladder, a frame for supporting the ladder, a rotary table for supporting the frame, a spring for holding the frame in its normal position, means operated by the movement of the frame against the spring out of its normal position to arrest the operating mechanism. 75

3. A salvaging apparatus having an extensible ladder, a frame for supporting the ladder, a rotary table for supporting the frame, operating mechanism for extending and telescoping said ladder, operating 80 mechanism for elevating and lowering said ladder, means for controlling said operating mechanisms, a movable element adapted to actuate the controlling members, means for moving the said movable element out of engagement with the controlling means when the frame is in its normal position, and means for moving the movable element into engagement with the controlling elements 85 upon movement of the frame out of its normal position. 90

4. A fire escape apparatus having an extensible ladder, a support, a frame for said ladder mounted upon said support, means for retaining said frame upon said support, 100 said means permitting a slight relative movement between said frame and said support, means resisting movement between the frame and said support, mechanism for extending and telescoping the ladder, mechanism for elevating and lowering the ladder, means actuated by movement of the frame relative to the support when the said resisting means is overcome to prevent actuation of said mechanisms. 105

5. A fire escape having a ladder, a support, a frame for said ladder mounted upon said support, connections between said frame and said support for retaining the frame upon said support while permitting a slight movement of the frame relative to said support, means for retaining said frame in a normal position upon said support and adapted to resist relative movement between the frame and the support, power operated mechanism for operating said ladder, means for controlling said power operated mechanism, and connections between said controlling means and said frame whereby the operating mechanism is arrested when the 110 frame and ladder move relative to said support. 115

6. A fire escape having a ladder, a support, a rotatable turntable mounted upon said support, a frame for said ladder mount- 120 125 130

- ed upon said turntable and arranged to have a limited amount of movement with respect thereto, means for holding the frame in a normal position upon said turntable and resisting relative movement between the frame and the table, the said means including a plurality of levers pivoted upon the bottom of said turntable, a spring connected to the inner ends of said levers, slidable members 10 contacting with the outer ends of said levers, and projecting through said turntable into engagement with a portion of said frame, and a movable member adapted to control the actuation of said operating mechanism, 15 the said controlling member being connected to the inner end of said levers.
7. A fire escape having an extensible ladder, a support, a rotatable turntable mounted upon said support, means for retaining 20 said table on said support, a frame carrying ladder mounted upon the upper face of said turntable and arranged to permit a limited amount of movement relative to the turntable, mechanism for extending and telescoping 25 the ladder, mechanism for elevating and

lowering the ladder, and means for automatically arresting the operation of the extending or inclining mechanisms when the stability of the ladder is endangered by an overload on the ladder, or when the ladder strikes an obstacle, the said means including oppositely arranged members slidably mounted in said turntable in the path of a portion of said frame, levers pivoted upon the lower surface of said table, the outer 30 ends of said levers supporting the lower ends of said sliding members, a rod depending from the inner ends of said levers, a spring surrounding said rod adapted to resist upward movement of the inner ends of 35 said levers, a movable member having its upper end arranged to engage a portion of the inclining and extending mechanism so as to prevent the actuation thereof when moving in an upward direction, the lower 40 end of said movable member being connected to the inner end of said levers.

In testimony whereof I affix my signature.

FRANZ HETZELBERGER.
